UNITED STATES PATENT OFFICE.

HERMANN HALTER, OF MUNICH, GERMANY.

METHOD OF BEDDING RAILROAD SLEEPERS WITHOUT TAMPING.

Application filed July 9, 1920. Serial No. 395,140.

(GRANTED UNDER THE PROVISIONS OF THE ACT OF MARCH 3, 1921, 41 STAT. L., 1313.)

To all whom it may concern:

Be it known that I, HERMANN HALTER, a citizen of the Republic of Germany, and residing at Munich, Kaulbachstrasse 60a, 5 Bavaria, Germany, have invented certain new and useful Improvements in Methods of Bedding Railroad Sleepers Without Tamping (for which I have filed an application in Germany, June 17, 1918, Patent 10 337,062), of which the following is a specification.

This invention relates to a method of bedding railroad sleepers without tamping and its object is to provide a stronger and more 15 durable form of bed than that obtained by packing ballast beneath the sleepers by tamping. This is accomplished by making the bed of reinforced concrete. The concrete is stamped layer after layer into the 20 iron skeleton or grids until the last horizontal layer reaches the height of the bottom surface of the sleepers, which are then put into place without any further packing or tamping operations being carried out. 25 The carrying capacity of the material thus stamped into the grids is much greater than that of a bed made by tamping. This elimination of the tamping operations is extremely important. In packing railway 30 sleepers great difficulty is encountered just at the points where the tamping is most necessary i. e. at the rail joints. This work is only done well by workmen who have had a long experience of railroad maintenance work and are painstaking and willing. 35

But these qualifications are often missing and are hardly ever possessed by temporarily employed hands upon whom the work of railroad maintenance now often 40 devolves. It can hardly be doubted that even where good workmen are available large sums have to be spent yearly for tamping work by which the supporting properties of the bed are only increased in a small 45 degree but which involves splitting of the sleepers at their bottom edges that results in the narrowing of their resting surfaces and in the bed being mixed with chips and splinters, and uselessly shattered and pul- 50 verized.

In the cases of railway beds constructed by piling up horizontal layers of material according to the new process the parts of the bed located beneath the rail-joints can

also be maintained without tamping. If for 55 any reason it should be necessary to raise the bed, as to make up for subsidence of the ground beneath, or to enable the sleepers to be newly adzed, this is done by lifting the section of rail in question by a few 60 centimeters (preferably by means of a rail lifting device), and by inserting a layer of concrete beneath the lifted sleeper.

This process is illustrated in the drawing in which Fig. 1 is a cross section of a 65 railroad with the right end of a sleeper slightly raised so as to permit of a layer of concrete being inserted beneath it. Fig. 2 shows a side view of a section of railroad in which an end view of the trough-like contrivance for sandwiching the concrete in 70 beneath the sleepers is shown beneath the second sleeper from the left, and Fig. 3 is a perspective view that illustrates the manner in which the sandwiching trough is 75 used.

Referring to the drawing, 10 designates a road bed constructed according to the present invention and composed of packed 80 layers of concrete. The road bed 10 is embedded therein near opposite sides and preferably at those portions where the rail joints are supported, with reinforcing gradings 11 which as shown comprise spaced apart and crossed bars of iron, steel or the like adapted to receive therebetween the concrete of which the bed 10 is composed. These gradings or reinforcements 11 are firmly embedded in the road bed and serve to hold the same from cracking and disintegration 85 incident to the vibration and weight imposed upon the road bed at these points. The road bed 10 is built up to the approximate surface level desired for supporting the ties 12, the ties maintaining the rails 90 13 in the usual manner.

The road bed 10 may be formed with one or more upper layers of the relatively fine stone or particles to provide a top packing surface. After the cementitious bed 10 is set the ties 12 may be properly elevated and leveled by resorting to the further method of this invention. During the formation of the road bed 10 the ties 12, if the trap is already laid, are removed or 100 arranged to one side so that the work of pouring the concrete and tamping the same in the reinforcements 11 may proceed with-

out interference. When it is desired to reset or adjust the ties 12 upon the road bed, the end of a tie 12 is elevated such as by use of a rail jack 14 of any suitable construction which is capable of lifting the adjacent rail 13 and the one or more adjacent ties connected thereto. When the ties are elevated, as shown in the figures of the drawing, a top layer of concrete or the like 10 may be laid in upon the road bed beneath the tie 12 by use of a special pan or receptacle 15 such as shown. The pan 15 is preferably made from sheet metal bent up at its opposite sides to form retaining 15 flanges and with the flanges spaced apart a distance slightly greater than the width of the tie 12. The upturned flanges of the pan are also outturned at their upper edges to provide finger holds 16 by means of 20 which the pan may be grasped in the hands and manipulated.

The concrete in plastic condition is placed in the pan 15 and the latter is slipped in between the raised end of the tie 12 and the 25 top surface of the road bed 10. The pan is moved in beneath the adjacent rail 13 to the desired extent and is then vibrated laterally, bringing the flanges 16 alternately against the sides of the rail with sufficient 30 force to jar the pan 15 and thus cause the plastic concrete to move within the pan. The pan is tilted up at its outer end as far as possible toward the under surface of the tie 12 to thus incline the pan and cause the 35 concrete to slide off of the same and be deposited on the upper surface of the road bed 10. While this shaking or vibrating operation is continued the pan is gradually drawn toward the end of the tie 12 so as to 40 deposit the concrete in a substantially uniform layer beneath the tie and longitudinally thereof. The operation may be repeated as many times as is necessary to build up the adjacent side of the road bed for 45 supporting the end of the tie 12 at the desired height.

Of course the rail 13 is maintained elevated until this new layer of concrete, designated as 16 in Fig. 1, sets. By use of this 50 pan an even layer of concrete may thus be placed beneath the ties without the necessity of tamping in beneath the tie from the sides and ends thereof which is found not to be satisfactory on account of the lack of 55 uniformity of the layer incident to such tamping.

This laying in of the layer of concrete 60 may be quickly and easily done at any portion or side of the track where it is necessary to rebed or reset the ties, and the layer 65 17 is uniform and may be applied in a relatively small space and with the expendi-

ture of but little time. It is also apparent that one workman may accomplish the resetting of the ties without the exercise of 65 any extraordinary skill.

What is claimed is:—

1. That method of rebedding railroad sleepers which consists in elevating the sleeper and introducing beneath the elevated 70 sleeper a pan open at opposite ends and with upstanding sides and containing a quantity of concrete in a plastic state, and tilting said pan and vibrating the same laterally to jar the pan against opposite sides of the 75 sleeper and move the same longitudinally beneath the sleeper for depositing a top layer of concrete on the road bed beneath the sleeper.

2. That method of building road beds 80 and setting ties which consists in laying layers of concrete with reinforcements near opposite sides of the road bed to the normal height to the bed, elevating the ends of the ties, and introducing beneath the elevated 85 ties a pan open at opposite ends and with upstanding sides and containing a quantity of concrete in a plastic state, and tilting said pan and vibrating the same laterally to jar the pan against opposite sides of the 90 ties and moving the pan longitudinally beneath the ties for depositing a top layer of concrete on the road bed beneath the ties.

3. That method of rebedding railroad 95 sleepers which consists in elevating the sleeper and introducing beneath the elevated sleeper a flat pan of greater width than the sleeper and having upstanding portions and containing a quantity of concrete in a plastic state, and tilting said pan and vibrating the 100 same laterally for jarring the pan against opposite sides of the sleeper to deposit a top layer of concrete on the road bed beneath the sleeper.

4. That method of rebedding railroad sleepers which consists in elevating the 105 sleeper and introducing therebeneath a flat pan open at opposite ends and having at opposite sides upstanding parts adapted to 110 engage opposite sides of the sleeper, and tilting said pan and vibrating the same to jar the pan against opposite sides of the sleeper and placing in said pan a quantity of concrete in a plastic state adapted to be 115 deposited upon the road bed beneath the sleeper.

In testimony whereof I affix my signature in presence of two witnesses.
